UNITED STATES PATENT OFFICE.

JOHN REID, OF NEW YORK, N. Y.

OIL-BURNING-FURNACE CONSTRUCTION.

1,322,343.

Specification of Letters Patent.

Patented Nov. 18, 1919.

Application filed August 14, 1919. Serial No. 317,537.

To all whom it may concern:

Be it known that I, JOHN REID, a subject of the King of Great Britain, and residing at 30 Church street, in the city of New York, 5 in the State of New York, in the United States of America, have invented a new and useful Oil-Burning-Furnace Construction, of which the following is the specification.

The invention relates to oil burning furnace front as described in the present specification and illustrated in the accompanying drawings that form part of the same.

The invention consists essentially in the novel means employed, whereby the flow of 15 air is so directed as to materially facilitate the combustion of the fuel gases and whereby the parts are arranged for ready installation and repair.

The objects of the invention are to 20 serve the fuel supply and at the same time obtain the maximum results at a minimum consumption of fuel; to insure a fair and even distribution of air in one or a plurality of furnaces arranged in a battery; to secure 25 despatch in equipping furnaces with fronts and effect quick repairs and replacements; to so construct and arrange the parts as to standardize such pieces likely to be most affected by the conditions under which the 30 fronts are used; and generally to provide a simple and efficient furnace front.

In the drawings, Figure 1 is a front elevation of the outer plate and mountings.

Fig. 2 is a front elevation of the back 35 plate, showing the intermediate parts in section.

Fig. 3 is a vertical sectional view of the furnace front.

Fig. 4 is a perspective detail of the central passage casing.

Fig. 5 is a diagrammatic view, showing the source and direction of the heated air.

Like numerals of reference indicate corresponding parts in each figure.

Referring to the drawings, the front plate 1 is shown with the upper opening 2 at or about the center and the lower opening 3, the former corresponding to the fuel opening and the latter to the ash opening in a 45 coal burning furnace front.

The opening 2 is closed by the plates 4 and 5, which are joined by the hinges 6. The upper plate 4 is secured by the bolts 7 in suitable slots and the lower plate 5 is secured by the bolts 8. In the upper plate 4

an aperture is stopped by the pivotally hung closure 9.

The lower opening 3 is closed by the hinged door 10 locked by the lever handle 11, the said opening 3 affording access to the 60 space between the front plate 1 and back plate 12.

The back plate 12 has a circular central opening 13, but is closed therebelow and above and has also the radial reinforcing 65 ribs 14.

The upper and lower air compartments 15 and 16 respectively between the plates 1 and 12 are formed by the upper wall 17 extending part way across the plates and above 70 the opening 13 and curved downwardly at each end terminating in the valve seats 18, and the flare 19 following the shape of the lower portion of the back plate 12 and terminating in the flanges 20 and valve seats 75 21. Both flare and upper air wall are preferably integral with back and front plates, though not necessarily so, still as a general rule they would form part of the same casting. The upper air compartment is preferably 80 divided centrally by the deflecting division plate 15^a also cast with the frame comprising back and front plates and intermediate fixed walls.

The lower compartment 16 is preferably 85 divided by the central deflecting division plates 16^a and 16^b, the plate 16^a being permanent with flare and back plate and the plate 16^b being secured to the door 10, each plate having suitable meeting edges. 90

This deflects the air reaching the lower compartment upwardly into the interior of the inner central air wall.

The valves 22 are pivotally mounted and close to the seats 18 and 21 and stop the 95 ports 23 and 24, which form the air inlets for the compartments 15 and 16.

The deflecting plates 25 and 26 of substantially crescent shape in cross section are rigidly secured to or form part with the 100 plates 1 and 12 and extend outwardly and downwardly at either side of the central opening 13 into proximity of the pivotal mountings of the valves 22.

The air is thus divided by the deflectors 105 25 and distributed to the upper and lower compartments.

The inner air wall 27 is of circular form at the rear end and flanged at 28 to engage the back plate 12 near the edge of the cen- 110

tral opening 13. The upper portion of the wall 27 extends to the front flange 29^a and the bottom 29 slopes upwardly from the rear flange 28 to the straight edge 30 of the flange 29^a. The bottom 29 is for the most part open forming an air port 31 while in the top portion are the air ports 32.

The usual practice is to combine three or more furnaces in one installation and in marine work the furnaces are grouped as shown in Fig. 5, the central furnace 33 being between the wing furnaces 34 and 35.

In order to insure an even and fair distribution of air, which is so much more essential in oil burning to secure satisfactory combustion, the heater chambers are preferably separate and individual to each furnace and front. The air flows down the passages 36, 37, 38 and 39, thereby equalizing the flow of air throughout the battery of furnaces.

In the operation of this invention, the skeleton frame of the front in the first place preferably comprises the front and back plates, the upper air compartment wall, the lower flare, and deflecting walls. To these are attached the lower door on the front plate and the closure plates to the central opening. The oil burner and accompanying parts of an oil fuel equipment are supported from the feed pipe projecting through the plate closure and these are all within the inner air wall, which thus becomes the burner casing. The latter is inserted from the back and rigidly secured by bolts, though readily removable for accessibility to the parts.

The air entering from the individual or other heaters as explained is deflected and therefore spreads to the upper and lower compartments, where it is again deflected with the result that the proportions of air are equally distributed throughout the whole oil vapor zone and become equally laden for burning, which guarantees better combustion and consequently greater heat and superior steaming qualities.

The individual heater chambers are shown as the most effective form of construction to bring out the best properties of the air pockets in the front, however many forms of heaters may be used with good results either the single type of draft air heater or other types.

Various changes may be made in the construction without departing from the spirit of the invention, and so long as they are within the scope of the claims for novelty following, the protection accorded shall not be invalidated.

What I claim is:—

1. In oil burning furnace construction, a frame formed of front and back plates and upper and lower spacing and connecting

walls separated by air ports, deflecting 65 plates at or near said ports, valves closing said ports, an oil burner and an inner air wall having suitable ports for feeding said burner.

2. In oil burning furnace construction, a 70 frame formed of front and back plates and upper and lower spacing and connecting walls containing air compartments having common ports, deflecting plates distributing the air to the upper and lower compartments, 75 an oil burner, valves closing said ports, and a removable central inner air wall having ports at top and bottom and secured to and bridging the space from back plate to front plate.

3. In oil burning furnace construction, a frame formed of front and back plates, lower flare and upper air wall, pivoted valves connecting said flare and air wall, an inner air wall having a circular inner end 85 secured to the back plate and converging to a lower straight edge resting on the front plate, said wall at top and bottom having air ports, closure plates hinged together and secured to the front plate and closing in said inner air wall, a lower door closing an opening in said front plate and an oil burner having a feed pipe projecting from said closure plate.

4. In oil burning furnace construction, a 95 plurality of furnace fronts having front and back plates and air compartments therebetween, valves closing ports to said compartments, inner air walls having distributing ports and heater chambers individual to 100 each furnace and discharging to passages leading to the several furnaces.

5. In oil burning furnace construction, a battery of furnaces formed of central and wing furnaces, an air heater chamber for 105 each furnace having passages approximately dividing the air equally between the furnaces, a front for each furnace having front and back plates and air compartments therebetween connected with said passages, valves 110 in said fronts, deflecting plates distributing the air from said heaters and oil burners in said fronts.

6. In oil burning furnace construction, a furnace front formed of front and back 115 plates and spacing and connecting walls forming an air pocket, having air ports thereinto from the sides, valves closing said ports, deflecting plates inside said ports, deflecting plates vertically arranged at the upper and lower ends, a burner, an inner central air wall surrounding said burner having upper and lower ports and means for feeding air under pressure to said pocket.

Signed at the city of New York this 2nd 125 day of Aug. 1919.

JOHN REID.
